(21) Appl. No.: **29/317,792**

(57) **CLAIM**

(22) Filed: **May 7, 2008**

The ornamental design for a soundproofing cover for engine generator, as shown and described.

(30) **Foreign Application Priority Data**

Nov. 9, 2007 (JP) 2007-031037

DESCRIPTION

(51) **LOC (9) Cl.** **13-01**

FIG. 1 is a perspective view of a soundproofing cover for engine generator showing our new design.

(52) **U.S. Cl.** **D13/122**

FIG. 2 is another perspective view thereof.

(58) **Field of Classification Search** D13/122,
D13/112, 114, 184, 199; D12/126, 216,
D12/410; D15/5; 290/1 A; 310/88, 89,
310/91, 272, 273; 322/100

FIG. 3 is a front elevation view thereof.

See application file for complete search history.

FIG. 4 is a rear elevation view thereof.

(56) **References Cited**

FIG. 5 is a top plan view thereof.

U.S. PATENT DOCUMENTS

FIG. 6 is a bottom plan view thereof.
